UNITED STATES PATENT OFFICE.

JOHN S. HOWK, OF RENO, NEVADA.

MOWING-MACHINE.

SPECIFICATION forming part of Letters Patent No. 590,987, dated October 5, 1897.

Application filed February 1, 1897. Serial No. 621,392. (No model.)

To all whom it may concern:

Be it known that I, JOHN S. HOWK, a citizen of the United States, residing at Reno, in the county of Washoe and State of Nevada, have invented certain new and useful Improvements in Mowing-Machines; and I do hereby declare the following to be a full, clear, and exact description of the invention, such as will enable others skilled in the art to which it appertains to make and use the same.

My invention relates to certain new and useful improvements in mowing-machines, and relates particularly to the cutting apparatus thereof, the object being to provide an antifriction-bearing between the stationary finger-bar and movable cutter-bar thereon in order to reduce friction and render more easy the action of the movable parts.

To this end my invention consists of a finger-bar provided with a series of fingers and overlapping bearing-plates, between which the cutter-bars move, and also a series of antifriction-rollers interposed beneath the said bearing-plates and between the stationary finger-bar and movable cutter-bar.

My invention also consists in certain other novel constructions, combinations, and arrangements of parts, as will be hereinafter described, and set forth in the appended claims.

In the accompanying drawings, Figure 1 is a top or plan view of a portion of the finger-bar, cutter-bar, and the parts thereof constructed in accordance with my invention. Fig. 2 is a similar view showing the bearing-plates removed. Fig. 3 is a cross-sectional view taken on a line through one of the confining-bolts of the bearing-plates. Fig. 4 is a bottom plan view of one of the bearing-plates on an enlarged scale. Fig. 5 is a cross-sectional view of the antifriction-roller, the confining-bolt, and parts on an enlarged scale. Fig. 6 is a longitudinal sectional view thereof, also on an enlarged scale, on line 6 6 of Fig. 1. Fig. 7 is an inverted plan view of the ring shown in Fig. 5.

Referring to the drawings, the letter A designates the main bar of the stationary finger-bar mechanism, provided, as usual, with a series of laterally-projecting fingers B, each having a guide-groove C, through which the cutter-bar or sickle D moves. These fingers are confined, as usual, to the finger-bar by bolts

f passing therethrough and through bearing-plates G thereon. Each of these bearing-plates has a central raised portion provided at each side thereof with ears g, each having slots for passage of the bolts, and with a laterally-confining extension g', which laps over upon the cutter-bar. In order to overcome the friction between the cutter-bar and finger-bar, I have provided these bearing-plates with a socket h on the under side thereof and an opening h' therethrough at the center of the socket, this socket at the side adjacent the confining projections being open. An antifriction-roller device occupies the said socket and comprises a bolt I, having at the lower end thereof a screw-head i, formed with an upper cone-shaped bearing-surface i'. The upper end of this bolt is adapted to pass through the said central opening in the bearing-plate and is threaded for the reception of a confining-nut i''. An antifriction-roller J also occupies the said recess or opening in the bearing-plate and comprises a ring having an exterior bearing-surface j projecting beyond the line of the central portion of the bearing-plate to a point just beyond the same and beneath the lateral confining-plate g' and bears against the inner or rear edge k of a movable cone. This antifriction-roller is provided with a circumferential internal groove j', forming a raceway for ball-bearings j''. The cone-shaped upper bearing-face i of the confining-rod bears against the under side of the bolts, and a movable cone k is fitted upon the shank of the confining-bolt and is adapted to be forced in contact with the balls on the other side thereof. By this construction a dust-proof antifriction-bearing is provided which diminishes the friction caused by contact of the cutting-members and facilitates easy operation thereof.

By screwing up the screw-shaped head of the confining-bolt or the nut on the upper end thereof the two cones heretofore mentioned may be adjusted relatively to each other and to the said ball-bearings to increase or diminish their freedom of movement and to compensate for wear thereof. It will be understood that the finger-bar will be provided with a series of these confining-plates and antifriction-bearings at regular intervals.

My invention provides a simple and effect-

ive antifriction-bearing for the cutting apparatus of mowing-machines and the like which practically reduces friction between the movable parts and renders the same much more 5 easily operated.

Having thus described the invention, what is claimed as new, and desired to be secured by Letters Patent, is—

1. In a cutting apparatus, the combination 10 with a fixed finger-bar and a movable cutter-bar, of bearing-plates located on said finger-bar having lateral projections bearing upon the cutter-bar, and an antifriction device comprising a roller bearing against the rear 15 edge of the said cutter-bar and having an internal ball-raceway and a confining-bolt passing through the said bearing-plate and having a fixed cone bearing on one side of the balls and a movable cone bearing on the op- 20 posite side thereof, substantially as described.

2. In a cutting apparatus for mowing-ma- 25 chines, the combination of a fixed finger-bar, a movable cutter-bar, a series of bearing-plates each having a central raised portion provided on the under side thereof with a 30 socket and at opposite sides with ears pro- 35 vided with openings for the passage of confining-bolts, an antifriction-roller occupying said socket and provided with a ball-raceway, a bolt passing through said roller and bearing-plate and provided with a head having a cone adapted to bear against one side of the balls in the raceway, and a movable cone bearing on the opposite side thereof said bolt having screw-heads for the reception of a confining-nut, substantially as described.

3. In cutting apparatus, for mowing-ma- 35 chines, the combination with a fixed finger- 40 bar and a cutter-bar movable thereon, of

bearing-plates located on said finger-bar and 45 provided with lateral projections extending over upon the cutter-bar, and a socket on the under side thereof, an antifriction-roller in 50 said socket and bearing against the inner edge of the cutter-bar, said roller consisting 55 of a hollow ring formed with an internal ball- raceway, and a bolt passing through the bearing-plate and provided at its lower end with a fixed cone and a movable cone, bearing on 60 opposite sides of the rollers, substantially as 65 described.

4. In cutting apparatus, the combination 70 with a fixed finger-bar and a movable cutter-bar, of bearing-plates secured to the finger-bar and provided with lateral projections ex- 75 tends over upon the cutter-bar and a socket on the under side thereof, a roller located in 80 said socket and adapted to bear against the rear edge of the cutter-bar, said roller consist- 85 ing of a ring formed with an internal cir- 90 cumferential chamber for the reception of antifriction-balls, a bolt formed at its lower end with a screw-head having its inner side 95 formed into a fixed cone and adapted to project over the opening in the under side of 65 the roller and bear against the antifriction- 100 rollers, and having its shank extending up through the bearing-plate and confined by a nut, and a movable cone surrounding the 105 said bolt and operating in the opening in the 70 top of the roller, substantially as described.

In testimony whereof I have signed this specification in the presence of two subscriving witnesses.

JOHN S. HOWK.
